UNITED STATES PATENT OFFICE

JOHN WYCLIFFE LEIGHTON, OF PORT HURON, MICHIGAN

BILLET CASTING MACHINE

Application filed October 24, 1929. Serial No. 402,139.

The principal objects of this invention are, to overcome numerous difficulties met with in the production of billets used in the manufacture of metal tubes by extrusion, and to provide a machine which will operate continuously without fouling the moulds and which will produce billets of uniform dimensions free from scale and grit.

A further object is to produce a machine of a very compact and rugged nature which will effectively dissipate the heat absorbed in the moulds from the molten metal poured thereinto.

The principal features of the invention consist first, in the novel construction of the moulds whereby a cooling medium is circulated therearound in such a manner as to rapidly dissipate the heat absorbed, and second, in the novel construction and operation of reciprocating plungers in the moulds whereby the billet is ejected and the mould surfaces are simultaneously cleaned and lubricated after the moulding of each billet.

A further feature of importance is in the novel construction of the machine whereby a plurality of moulds are mounted upon a rotatable member and the ejecting mould clearing plungers in the several moulds are automatically operated in progressive rotation.

In the drawings, Figure 1 is a plan view of the machine in part horizontal section.

Figure 2 is a vertical longitudinal section of the machine on the line 2—2 of Figure 1.

Figure 3 is a vertical section on the line 3—3 of Figure 1.

Figure 4 is a horizontal section through the line 4—4 of Figure 2 (enlarged).

The device herein shown is constructed with a hollow base 1 having a raised side wall 2 extending completely therearound.

One end of the base is of semi-circular form and has a raised circular bed portion 3 on which is rigidly mounted a hollow cylindrical standard 4 provided with a flanged base 5.

An annular flange 6 extending outwardly from the standard 4 adjacent to its lower end supports a ball bearing 7 upon which is mounted a casting 8 which has a central cylindrical portion encircling the standard,

the upper end of which is guided by a ball bearing 9.

The casing 8 is formed with a plurality of radially arranged part cylindrical extensions 8' which are spaced equidistant around the central portion and form a part thereof. 55

A circular flange 10 forms part of the casting 8 and upon this flange is supported a cylindrical apron 11 which extends downwardly and is provided with a double flanged bottom edge which extends over the upper tapered edge 12 of a flanged ring 13 secured to the top of the side wall 2 and which forms part of a cap closing in the hollow base. 60

Each of the radial extensions 8' are bored vertically parallel with the axis of the standard 4 and bearing sleeves 14 and 15 are axially arranged in each of the bored extensions. 65

A plunger 16 is slidably mounted in each of the extensions 8' and the upper end of the plunger has arranged thereon a piston head 17 which engages the upper bearing sleeve 15 in a snug sliding fit. 70

The piston head 17 is formed with a longitudinal recess 18 on one side, and a partition wall 19 which is spaced from the centre pin, hereinafter described, is provided with a longitudinal slot 20 radially opposite the recess 18 and an opening 21 at the top 80 through which the oil or other cooling medium flows from the recess 18 to the slot 20 flowing around the centre pin. 75

Circumferential recesses 22 are formed in the casting 8 surrounding the upper part of each of the sleeves 15 and a vertical passage 23 is arranged to connect each recess 22 with radial openings 24 which are in constant communication with the recesses 18 of the pistons. 85

Radial passages 25 extend inwardly from the chamber 22 to the circumferential recess 26 in the inner wall of the rotatable member 8 and the latter recess is connected with a chamber 27 in the top of the standard 4 by a plurality of radial passages 28. 90

A transverse partition 4' in the central chamber of the cylindrical standard 4 is arranged immediately below the radial pas- 100

sages 28 and separates the upper part of the standard from the lower part.

The chamber 27 in the standard has connected thereto a pipe 29 which conveys a fluid cooling medium through the top of the standard which flows outwardly through the 5 passages 28 into the circular recess 26 in the rotatable casting and then through the radial passages 25 to the recess 22 surrounding the 10 bearing sleeves 15 effectively cooling the upper portion of the sleeves into which the molten metal is poured. The cooling medium then flows from the recesses 22 through the vertical passage 23 to the passage 24 from 15 whence it flows into the longitudinal passage 18 in the piston through the opening 21 in the top of the partition 19 and the longitudinal slot 20 and out through radial passages 30 arranged opposite the passages 24, to a 20 circumferential recess 31 arranged below the recess 26 which communicates with radial passages 32 in the standard 4 which lead to the inner chamber 33 of the cylindrical standard below the partition 4'. 25 It will be noted that the cooling fluid flowing through the opening 21 in the piston is directed against the pin 36 extending axially through the piston and impinges on said pin at the top of the slot 20 as the piston travels 30 up and down.

The cooling medium flows out from the bottom of the hollow standard into the hollow base from whence it is carried in a return circulation to the upper feed pipe 29 35 by means of a suitable pump, which is not shown, and such cooling medium is preferably conducted through suitable heat dissipating radiators.

Each of the plungers 17 is formed with a 40 longitudinal slot 34 adjacent to the upper end and a cross bar 35 extends through said slot and is supported in the casting 8 at each end.

A pin 36 is secured in each cross bar 35 45 and extends upwardly through a central orifice 37 in the piston end of the plunger 17 and forms the centre pin for the billets to be cast in the mould formed by the sleeve 15 and the top face of the piston 17.

50 It will be noted that the centre pins are rigidly supported by the cross bars 35 while the plungers are capable of moving with a reciprocating motion in the bearing sleeves in the casting 8.

55 The moulds herein shown are provided with centre pins to form billets with a central orifice but when solid billets are desired the pins will be eliminated and the piston will be closed at the top.

60 Each plunger is provided at its lower end with a transverse slot 38 in which is arranged a roller 40 mounted upon a pin 41.

65 A cam 42 which has a gradual rise to one side of the machine is mounted upon the flanged base 5 of the standard and engages

the rollers 40 of the plungers to move them upwardly.

Rollers 43 are arranged on the inner ends of the pins 41 and a cam 44 is mounted on the standard 4 to engage the rollers 43 to draw 70 the plungers downwardly.

A toothed gear ring 45 is secured to the casting 8 adjacent to its lower end, said gear ring being preferably located below the top 75 of the side wall 2 of the hollow base.

A block 46, preferably forming part of the bottom of the base structure extends upwardly within the hollow base in a position centrally of the width of the squared end 47 of the base.

A step bearing 48 is arranged in the top of the block 46 and supports a stub shaft 49, the upper end of which is journalled in a bearing 50 in the cap section 51 of the ring 13 secured to the hollow base. 80

A gear pinion segment 52 mounted on the shaft 49 meshes with the gear ring 45 to operate the rotatable member. 85

A bevelled gear 53 also mounted on the stub shaft 49 meshes with a bevelled pinion 54 mounted on a shaft 55 which extends transversely of the base 1 and is mounted in the bearings 56 and 57 therein. 90

One end of the shaft 55 extends beyond the casing and is driven by suitable means and a packing gland is arranged to seal the shaft opening against the leakage of oil from the base. 95

A pawl 59 is pivotally mounted on a pin 60 extending vertically upward from the bottom of the base, said pawl having a toothed end 61 adapted to engage the teeth of the gear ring 45 to hold the gear ring in a fixed position. 100

A coil compression spring 62 is arranged to operate the pawl into engaging contact with the gear. 105

The pawl is provided with an arm 63 which is engaged by a cam 64 mounted on the hub of the bevelled gear 53 or upon the shaft 49. 110

The gear pinion 52 is a segment only and is arranged to rotate the member 8 a predetermined distance and then disengage from the gear ring. 115

The cam 64 and pawl 59 co-operate to engage and hold the gear ring in a definite fixed position while the gear pinion segment 52 is rotating free and the arrangement of the pawl ensures the meshing of the teeth 52' 120 when the pinion moves around in the completion of its rotation.

The operation of the rotatable member is, because of its arrangement of mechanism, intermittent, consequently the moulds rest for a definite period at which time the metal to be cast into a billet is poured into same. 125

Immediately after the filling of the mould formed by the sleeve 15 the subsequent movement of the member 8 moves the plunger up 130

wardly stripping the billet from the centre pin and lifting the billet from the mould.

The head of the piston sliding within the sleeve 15 removes all scale or particles of carbon or oil residue therefrom, thus clearing the wall of the mould and it also strips any material adhering to the pin.

In its upward movement the piston carries with a body of oil which acts as a further cooling element to cool the mould as in the rising of the piston the oil covers practically the entire surface of the sleeve 15 and also completely surrounds the pin 36.

The contact of the circulating body of cooling oil not only cools the metal but it covers the surface with a film of oil which prevents the adhesion of oxides of the metal poured into the mould.

Billets cast in a machine such as described are uniform in size and texture of metal; as the conditions of cooling and shrinkage are very uniform.

The surfaces in contact with the poured metal are very smooth, consequently the billet produced has a smooth exterior free entirely from grit, such as is assimilated from sand moulds.

An arm 65 is secured to the upper end of the standard 4 and projects angularly across the top of the rotatable member in such a manner as to guide the finished billets off the top of the machine as it rotates.

It will be understood from this description that a machine constructed as described is very compact and the top is of such a height that the moulds are easily available for pouring from the ordinary ladles.

It will be noted that the cooling medium, which is preferably also a lubricant, is circulated around and through the moulds and is carried through the hollow standard to the hollow base where the operating mechanism is immersed in such medium and all parts are thoroughly lubricated and cooled.

In the construction of machine herein shown and described the rotating mould member is periodically arrested but it may be found desirable to operate the machine without arresting the moulds and this can be accomplished by simply using a complete pinion in place of the segment 52 and dispensing with the pawl 59 and cam 64.

It may also be found desirable to provide means for scraping the top surface of the moulds immediately after the pouring of the metal to remove any slag or scale.

What I claim as my invention is:—

1. A billet casting machine, comprising a mould, a plunger reciprocable in said mould and forming the bottom thereof, and means for circulating a liquid cooling medium around said mould and said plunger.

2. A billet casting machine, comprising a mould, a plunger reciprocable in said mould and forming the bottom thereof, and means

for directing a lubricant around the inner surface of the mould following the discharge of the billet therefrom.

3. A billet casting machine, comprising a mould, a plunger reciprocable in said mould and forming the bottom thereof and having a transverse passage therethrough, and means for circulating a cooling and lubricating medium around the mould and through the passage in said plunger to effect the cooling and lubrication of the mould. 70 75

4. A billet casting machine, comprising a mould, a plunger reciprocable in said mould and forming the bottom thereof, a passage encircling the mould, a passage extending transversely through said plunger, and a passage leading from the aforesaid passage and communicating with the passage in the plunger and conducting the fluid lubricant in a continuous flow therethrough. 80 85

5. A billet casting machine, comprising a mould open at the top, a plunger reciprocable in said mould and forming the bottom thereof, a pin fixed axially of the mould and in slidably engagement with the plunger, a passage through the plunger around said pin, a passage around the mould communicating with the passage through the plunger, and means for directing a flow of cooling and lubricating fluid around the mould and through the plunger. 90 95

6. A billet casting machine, comprising a tubular mould, a pin fixed axially within the mould, a plunger slidable within the mould and in sliding engagement with said pin, said plunger having a longitudinal recess opening at one side thereof and a passage around the pin communicating with said longitudinal recess at the top, the outer side of said passage on the side of the plunger opposite to the longitudinal recess extending longitudinally of the plunger, a body surrounding said tubular mould having passages communicating through openings in the mould with the longitudinal recess and longitudinal passage in the plunger; and a conduit extending around the upper and open end of the tubular mould conducting a fluid cooling and lubricating medium to the aforesaid passages. 100 105 110 115

7. A billet casting machine, comprising a rotatable member having a plurality of mould recesses therein, a plunger operable in each of said recesses, means for operating said rotatable member, and means for operating said plungers progressively in said moulds during the rotation of the rotatable member. 120

8. A billet casting machine, comprising a rotatable member having a plurality of mould recesses, a reciprocable plunger arranged in each of said mould recesses, means for rotating said rotatable member, means for operating said plungers to eject the moulded billets from the moulds, means for maintaining a continuous flow of a cooling lubricating 125 130

medium around said moulds, and means for applying said fluid lubricating medium to the inner walls of said moulds.

9. A billet casting machine, comprising a vertical standard, a member rotatably mounted on said standard having a plurality of vertical moulds, a plunger reciprocable in each of said moulds, means supported by said standard for reciprocating said plungers, means for rotating said mould carrying member, and means for circulating a cooling medium through said standard and around said moulds.

10. A billet casting machine, comprising a vertical standard, having a central chamber in the top communicating with a cooling medium supply and having a plurality of radial passages, a member rotatably mounted on said standard having a plurality of moulds therein, cooling chambers encircling said moulds, passages maintaining constant communication between the chamber in said standard and the chambers encircling said moulds, means for conducting the fluid medium from the mould encircling chambers, means for rotating the rotatable mould member, and means for ejecting the billets from the mould and clearing the moulds.

11. A billet casting machine, comprising a hollow standard having a partition thereacross and radial passages above and below said partition, a member rotatably encircling said standard having annular chambers communicating respectively with the upper and lower sets of said radial passages, radial passages leading outwardly from said annular chambers, mould cavities arranged in said rotatable member, chambers surrounding said mould cavities connected with the upper set of radial passages, passages leading from the mould encircling chambers and leading through the mould cavities to the lower set of radial passages and the hollow standard below the partition, and a plunger operating in each of said mould cavities having passages therethrough to conduct the fluid cooling medium to and through the mould cavities.

12. A billet casting machine, comprising a mould open at the top, a centre pin fixed in said mould, a plunger slidably engaging the mould walls and the walls of said pin and adapted to be projected beyond the top of the mould, said plunger having a passage extending transversely therethrough surrounding the pin, means for reciprocating said plunger, and means for circulating a cooling lubricating medium through the passage in the plunger.

13. A billet casting machine, comprising a vertical standard, a member rotatably mounted on said standard having a plurality of vertical moulds, a plunger reciprocable in each of said moulds, means supported by said standard for reciprocating said plungers,

means for circulating a cooling medium around said moulds and through said standard, a gear ring on said mould member, a gear pinion meshing with said gear ring, and means for rotating said pinion.

14. A billet casting machine, comprising a vertical standard, a member rotatably mounted on said standard having a plurality of vertical moulds, a plunger reciprocable in each of said moulds, means supported by said standard for reciprocating said plungers, means for circulating a cooling medium around said moulds and through said standard, a gear ring on said mould member, a gear segment meshing with said gear ring, a pawl adapted to engage and hold said gear ring, and a cam rotating with said segment operatively engaging said pawl.

15. A billet casting machine, comprising a hollow base, a hollow standard mounted in said base, a member rotatably mounted on said standard having a plurality of vertical moulds therein, a plunger operating in each of said moulds and extending into said base, cams on said standard engaging said plungers, means for circulating a cooling lubricating medium around said moulds and through said standard and base, and means mounted in the hollow base for rotating said mould member.

16. A billet casting machine, comprising said base, a member rotatably mounted on said base, a member rotatably mounted on said standard having a plurality of vertical moulds therein, a plunger operating in each of said moulds and extending into said base, cams on said standard engaging said plungers, means for circulating a cooling lubricating medium around said moulds and through said standard and base, a shaft extending transversely of said base, a bevel gear mounted on said shaft, a bevel pinion meshing with said bevel gear and rotatably mounted in said base, a gear segment secured to said pinion, a gear ring mounted on said rotatable mould member meshing with said segment, and means for intermittently holding said gear ring and mould member.

17. A billet casting machine, comprising a base having a raised side wall extending therearound, a cap closing the base having a ring flange projecting thereabove, a standard mounted in said base, and arranged centrally of said ring flange, a rotatable member encircling and mounted on said standard and having a plurality of moulds therein, a cylindrical apron secured to said mould member and extending downwardly over said ring flange, means enclosed within said base for rotating said mould member, a plunger operating in each of said moulds and extending into said base, and means for circulating a lubricating medium around said moulds and through said base.

18. In a billet casting machine, a sleeve

mould having openings oppositely arranged intermediate of the length thereof, a casing encircling said sleeve having an annular chamber surrounding the upper end of said sleeve and a passage leading from said chamber to one of the openings of said sleeve, a discharge passage in said casing leading from the other opening in the sleeve, a passage in said casing leading to said chamber, 5 a pin fixed axially in said sleeve, and a plunger slidably arranged on said sleeve and slidably engaging the inner wall of the sleeve, said plunger having a recess extending longitudinally of one side communicating with 10 the opening in the sleeve connected with the encircling chamber and a longitudinal slot in the opposite side surrounding said pin and communicating with the discharge passage and a passage connecting said longitudinal 15 recess and slot at the top, and means for reciprocating said plunger.

19. A billet casting machine, comprising a casting having a vertical chamber, a sleeve within said chamber, a bar extending across 20 said chamber, a pin rigidly secured in said bar and extending axially of said chamber, a plunger slidably arranged in said sleeve having a longitudinal slot therethrough through which said bar extends and a piston 25 head thereabove slidably encircling said pin, a passage extending transversely through the piston head of said plunger, a passage surrounding the upper end of said sleeve and connected with the passage through said 30 plunger, and means for operating said plunger.

20. A billet casting machine, comprising a rotatable member having a plurality of mould recesses therein, a plunger operable 35 in each of said recesses, means for operating said rotatable member, means for reciprocating said plungers, and means for clearing the top surface of the metal poured into said moulds.
